HOLLOW RESONATOR DISCHARGE DEVICE

Albert Frederick Pearce, Hampton Hill, England,
assignor to Electric & Musical Industries Limited, Middlesex, England, a company of Great Britain

Application September 25, 1945, Serial No. 618,548
In Great Britain October 18, 1941

Section 1, Public Law 690, August 8, 1946
Patent expires October 18, 1961

4 Claims. (Cl. 315—5)

1

This invention relates to electron discharge devices employing hollow resonators.

Various constructions of such devices have heretofore been proposed in which an electron beam is caused to pass through apertures in the walls of a toroidal-shaped body forming the hollow resonator. The electron beam on passing through the resonator becomes velocity-modulated and the velocity-modulated beam may then be reflected back through the apertures in the resonator so that the device can serve as a generator of self-maintained oscillations. Alternatively, the velocity-modulated beam may be caused to pass through apertures in a further hollow resonator, these two resonators being suitably coupled for the generation of self-maintained oscillation. Other constructions of discharge devices employing hollow resonators are known, the devices being suitable for use as detectors, amplifiers and mixers of oscillations of ultra-high frequency.

In general, the hollow resonators require to be tuned to the operating frequency and for this purpose the dimensions of the hollow resonator are so chosen that it resonates at a desired frequency, slight adjustment of this frequency being, however, possible by de-forming the resonator. It will be appreciated that it is necessary for that part of the resonator through which the electron beam passes to be disposed within an evacuated dielectric envelope and consequently constructional difficulties are entailed where it is desired to effect adjustment of the resonant frequency by de-forming the resonator.

The object of the present invention is to provide an improved construction of electron discharge device employing one or more hollow resonators which will permit of ready adjustment of the resonator for tuning purposes.

According to the invention an electron discharge device employing a hollow resonator is provided having apertures through which an electron discharge can pass, said apertures being located within an envelope and lying between the center of the resonator and its periphery, said envelope having a re-entrant portion across which the central part of the resonator extends, whereby said central part is external to the envelope. Where it is desired to tune the resonator the tuning means are arranged to extend into the re-entrant portion and to co-operate with that part of the resonator which extends across the re-entrant portion. With such an arrangement the mechanical construction necessary for the deformation of the resonator is considerably

2

simplified as will hereinafter be apparent. Preferably, the apertures in the resonator are of annular form and the electron beam in cross section is also preferably of annular shape which has the advantage of permitting the voltage applied to the resonator to be reduced owing to the consequent large emitting area of the cathode.

In order that the said invention may be clearly understood and readily carried into effect, it will now be more fully described with reference to the accompanying drawing which illustrates in longitudinal section one embodiment of an electron discharge device constructed according to the invention. As shown, the reference numeral 1 indicates an evacuated dielectric envelope having a re-entrant portion 2 through the wall of which portion the hollow resonator indicated generally at 3 is sealed. The hollow resonator is generally of toroidal form having the section 20 shown and the aperture through which the electron beam passes is of annular form as indicated at 4. Electrons from an annular cathode 5 are caused to pass through the annular aperture 4 and are directed towards a ring-shaped reflecting electrode 6 which is maintained at a suitable potential to cause the electron beam to be reflected back through the annular aperture. The device shown in the drawing is intended to be employed as a generator of self-maintained oscillations and is suitable for use as a low powered local oscillator for a superheterodyne receiver, the oscillator operating in the region of 10,000 megacycles. The invention is of course not limited to any particular frequency. Any suitable construction of electron focussing system may be employed for focussing the electrons emitted from the cathode 5 and in the example shown a pair of ring-shaped electrodes 7 are employed for focussing purposes. The cathode 5 and the electrodes 7 may be supported in any suitable manner from a stem 8 which carries the usual exhaust tube 9. The reflecting electrode 6 may be supported in any suitable manner and in the example shown it is carried by rods 10 sealed to the periphery of an annular collar 11 connected to the re-entrant portion 2.

It will be seen that the annular aperture 4 lies between the center of the resonator and the periphery and that the central part of the resonator extends across the re-entrant portion 2 and hence such portion is disposed external to the envelope. Consequently, this portion of the resonator can be readily de-formed for tuning purposes and the mechanical construction necessary for such deformation can be of a relatively simple character. As shown, the tuning mechanism comprises

a rotatable shaft 12 having a suitable knob 13 the shaft being constrained against axial movement and being rotatably mounted in a support 14 which is secured to the envelope. The lower end of the shaft 12 is provided with a screw-threaded portion 15 which engages a screw-threaded sleeve 16 which is secured to the part 17 of the wall of the resonator which extends across the re-entrant portion 2, the part 17 of the resonator being corrugated, as shown, so as to permit said part to move towards or away from the opposite wall of the resonator during tuning. Thus, when the shaft 12 is rotated the sleeve 16 is moved axially and hence moved towards or away from the opposite wall of the resonator. This opposite wall is provided with a re-entrant portion 18 so that tuning is effected by adjusting the effective capacity between this re-entrant portion and the sleeve 16. Other ways of tuning the resonator can of course be employed. Further means may be provided for enabling a coarse and fine adjustment of the resonator to be obtained. The re-entrant portion 2 may also serve to accommodate a concentric line 19 which terminates in a coupling loop 20 projecting into that portion of the resonator extending across the re-entrant portion 2 and which serves as the output for the generated oscillations.

It will be seen from the drawings that part of that portion of the dielectric envelope forming the re-entrant portion 2 lies between the walls of the resonator and preferably this portion of the envelope is arranged to lie at a position where a voltage node is set up in accordance with the invention described in the specification of British Patent 574,708.

The outer portion of the hollow resonator indicated by the reference numeral 21 may be supported in any suitable manner in relation to the other portion of the hollow resonator and it may also be desirable to short-circuit the annular gap at a number of points around its periphery by means of thin bars or wires radially arranged for the purpose of ensuring the proper phase relationship of the oscillations set up in the portion 21 of the resonator and in the remainder of the hollow resonator. These thin bars or wires should extend between adjacent edges of the resonator which form the aperture in both walls of the resonator.

In one form of the invention the cathode 5 may be of the indirectly heated oxide type having a width of 2 millimetres and the diameter of 25 millimetres such a cathode being capable of emitting a current of over 200 milliamperes. With such a large current flow it is possible to operate the device with a potential of the order of 250 volts applied to the hollow resonator which is low compared with the potentials necessary in devices where the current flow is considerably less than that referred to above. With such a large current flow the width of the gap can be small thus enabling greater efficiency to be obtained. Furthermore, owing to the large cathode emissive area which is available, it is possible that the device may find application for the generation of oscillations of high peak power by applying to the hollow resonator pulses of high voltage and short duration. If the device is so used, peak powers of the order of kilowatts may be obtainable.

Although the invention has been described above as applied to an oscillator in which a velocity-modulated beam is reflected back through the resonator, it will be understood that the inven-

tion is equally applicable to electron discharge devices employing one or more hollow resonators when designed for use for other purposes.

In particular, the device shown in the drawing may be employed for mixing high-frequency oscillations, in which case the intermediate frequency output may be taken from the electrode 6 which, in this example, may serve as a target electrode for the higher velocity electrons in known manner. Further, the invention is not limited to devices employing velocity-modulation, since the invention may be applied to devices in which a hollow resonator forms the input circuit of a conventional form of thermionic valve.

If desired, the re-entrant portion 2 may be extended so as to provide a support for the annular cathode 5 and the focussing electrode 7. The cathode and focussing electrodes may be mounted on rings of insulating material so as to form a unitary structure and the inner edges of said rings may engage a plurality of protrusions formed in the portion 2 and extending into the evacuated space whereby the structure can be aligned with respect to the apertures 4 similar to the arrangement described in the specification of British Patent No. 507,840. Likewise, the electrode 6 may be mounted on rings of insulating material and aligned by the provision of protrusions formed in the portion 2. In some cases the re-entrant portion may extend along the whole length of the envelope 4, so that the envelope, together with the re-entrant portion, provides an evacuated space of annular cross-section along its length. Such a construction is particularly suitable where two resonators are employed since it permits both resonators to be tuned by tuning mechanisms disposed at opposite ends of the envelope.

For high powered devices cooling arrangements may be necessary. For example, the hollow resonator or resonators may be provided with cooling fins. Further, in the construction shown in the drawing, water cooling of the re-entrant portion 2 may be employed. Where the re-entrant portion extends along the whole length of the envelope, air or water may be forced along the re-entrant portion entering at one end and being exhausted at the other end, suitable apertures being provided in the portion of the resonator or resonators extending across the re-entrant portion to permit of a through flow of air or water.

What I claim is:

1. An electron discharge device having an evacuated envelope provided with a tubular re-entrant portion, a cavity resonator sealed through the walls of said tubular re-entrant portion with a portion of the resonator within the evacuated envelope and another portion within said tubular re-entrant portion and external of said envelope, said cavity resonator being apertured in the portion within said envelope, means for directing an electron stream through said apertured portion and means for collecting said electron stream, said last two means being within said evacuated portion of said envelope, a portion of the wall of said cavity resonator portion external of said evacuated envelope being flexible, and means for flexing said flexible wall portion for tuning said resonator.

2. An electron discharge device having an evacuated envelope provided with a tubular re-entrant portion, a cavity resonator extending transversely of the tubular re-entrant portion of

said envelope with a portion of said resonator external of said envelope and a portion within said envelope, the walls of said resonator being sealed through the walls of the tubular portion of said envelope, said resonator being provided with an apertured portion adjacent its periphery and within said evacuated envelope, an annular cathode means within said envelope registering with the apertured portion of said resonator for directing electrons through said apertured portion, an annular collector associated with said resonator for receiving said electrons, one wall of the resonator within the reentrant portion of said envelope and outside the evacuated portion of the envelope being corrugated for rendering said wall flexible, and means for flexing said resonator wall for tuning said resonator.

3. An electron discharge device having an envelope provided with a tubular reentrant portion, a cavity resonator extending transversely of the tubular reentrant portion of said envelope with a portion of said resonator external of said envelope and a portion within said envelope, the walls of said resonator being sealed through the walls of the tubular portion of said envelope, said resonator being provided with an apertured portion adjacent its periphery and within said evacuated envelope, an annular cathode means registering with the apertured portion of said resonator for directing electrons through said apertured portion and annular collector for receiving said electrons, one wall of the resonator within the reentrant portion of said envelope being corrugated for rendering wall flexible and means for flexing said wall for tuning said resonator, said last means comprising a threaded element supported by said flexible wall and screw

element rotatably supported at the open end of said tubular portion for causing movement of said threaded element for flexing the wall of said resonator for tuning said resonator.

- 5 4. An electron discharge device having an evacuated envelope provided with a tubular reentrant portion, a cavity resonator extending transversely of the tubular reentrant portion of said envelope with a portion of said resonator external of said envelope and a portion within said envelope, the walls of said resonator being sealed through the walls of the tubular portion of said envelope, said resonator being provided with an apertured portion adjacent its periphery and within said evacuated envelope, an annular cathode means within said envelope registering with the apertured portion of said resonator for directing electrons through said apertured portion, an annular collector associated with said resonator for receiving said electrons, one wall of the resonator within the reentrant portion of said envelope and outside the evacuated portion of the envelope being flexible, and means for flexing said resonator wall for tuning said resonator.
